(57) **CLAIM**

The ornamental design for an aircraft luggage bin, as shown and described.

DESCRIPTION

FIG. 1 is a front isometric view of an embodiment of an aircraft luggage bin showing my new design in a typical environment.

FIG. 2 is an isolated front isometric view thereof.

FIG. 3 is a front cross-sectional view thereof, the rear cross-sectional view being a mirror image.

FIG. 4 is a right-side cross-sectional view thereof.

FIG. 5 is a bottom view thereof.

FIG. 6 is a front isometric view of another embodiment of an aircraft luggage bin showing my new design in a typical environment.

FIG. 7 is an isolated front isometric view thereof.

FIG. 8 is a front cross-sectional view thereof, the rear cross-sectional view being a mirror image.

FIG. 9 is a right-side cross-sectional view thereof; and,

FIG. 10 is a bottom view thereof.

Features indicated in broken lines in the accompanying drawings form no part of the corresponding embodiment.
